A. KENNEDY,
HYDRAULIC BACK PRESSURE VALVE,
APPLICATION FILED JUNE 20, 1919.

1,367,189.

Patented Feb. 1, 1921.

UNITED STATES PATENT OFFICE.

ANGUS KENNEDY, OF LONDON, ENGLAND.

HYDRAULIC BACK-PRESSURE VALVE.

1,367,189.

Specification of Letters Patent.

Patented Feb. 1, 1921.

Application filed June 20, 1919. Serial No. 305,714.

To all whom it may concern:

Be it known that I, ANGUS KENNEDY, subject of the King of Great Britain and Ireland, residing at 236-8 Pentonville road, 5 London, in the county of London, England, have invented certain new and useful Improvements in Hydraulic Back-Pressure Valves, of which the following is a specification.

10 My invention relates to improvements in hydraulic back pressure valves particularly of the type used in conjunction with oxy-acetylene welding apparatus wherein a water seal is used to prevent oxygen from the blowpipe from passing into the pipe leading from the acetylene gas holder or generator.

A known type of safety valve consists of a closed cylindrical chamber having inlet and outlet cocks for the acetylene gas. The 20 gas is led to the base of the chamber through a tube or pipe connected to the inlet cock and is discharged into the chamber beneath a water seal formed in the lower part of the apparatus. A second tube arranged 25 above the lower open end of the supply pipe and below the water level, leads to a chamber or box open to the atmosphere and arranged outside said chamber.

The object of the present invention is to 30 provide a safety valve which will present a more effective and reliable safeguard against explosion than is obtained by the type at present in use.

According to the invention the device 35 consists of two cylindrical or other suitably shaped chambers arranged, preferably, side by side. The top of the first chamber carries the usual connections leading to the gas holder or generator, and a downwardly 40 extending supply pipe terminating at its lower end in a perforated chamber at or near the bottom of the valve chamber. At a convenient distance from the bottom this chamber communicates with a second chamber 45 by means of a pipe or tube whose outer end is bent downwardly to a point a short distance from the bottom of the second chamber. Within the second chamber is also arranged an escape pipe extending 50 from a point a short distance from the bottom of the chamber, but preferably level with or above the lower open end of the communicating pipe, through the top of the chamber to the atmosphere. Both chambers 55 are provided with water level cocks by means of which the level of water in each chamber

may be ascertained and regulated. The second chamber is also provided with the usual cock by means of which the pipe leading to the blowpipe or the like is connected.

In order that the invention may be readily understood reference is directed to the accompanying drawings showing by way of example a valve constructed according to the invention in which:

Figure 1 is a side elevation, and
Fig. 2 is a transverse vertical section of
Fig. 1.

The apparatus is built up of two cylindrical or other conveniently shaped chambers *a* and *b* arranged side by side. The chamber *a*, hereinafter referred to as the first chamber, is provided with a port *c* connected to a pipe leading to the acetylene 70 generator or gas holder, by a nozzle or union joint *d*. This port is formed with, or connected to, a pipe or tube *e* extending to a point a short distance from the bottom of the chamber *a* its lower end terminating 75 in the usual perforated metal or gauze box or casing *f*. At a suitable distance from the bottom of the chamber is a pipe *g* communicating with the second chamber *b*, the outer end of the pipe being bent downwardly at *g*¹, so as to terminate preferably 80 a short distance from the bottom of the chamber *b*. Within the chamber *b* is also secured a vertical escape pipe *k* extending from a point, either level with, or slightly 85 above, the lower open end of the connecting pipe *g*¹, while its upper end, which extends outside said chamber, may have an open inverted cone or funnel-shaped vessel *l*. Both chambers *a* and *b* are provided with 90 water level regulating cocks *m*, by means of which the level of water in each of the chambers may be ascertained and regulated.

The second chamber *b* is also provided with the usual controlling cock *n* and nozzle *n*¹ to which the supply pipe leading to the blowpipe or the like is connected.

The pipe *g* connecting the two chambers may be secured thereto in any suitable manner.

105 The operation of the apparatus is as follows:

During normal working, the acetylene gas passes through the port *c* into the first chamber *a* and thence into the second chamber *b* 110 through the connecting pipe *g*, *g*¹, after which the gas passes through the nozzle *n*¹

to the delivery pipe connected to the blowpipe or the like.

Should the nozzle of the blowpipe become choked or blocked from any reason, the oxygen will be forced under pressure through the acetylene delivery pipe connected to nozzle n^1 into the chamber b . In this case the water in said chamber will be displaced through the pipe g, g^1 , into the chamber a wherein it rises until the open upper end of the connecting pipe g^1 is below the water level. Meanwhile the level of water in the chamber b will fall below the lower open end of the escape pipe k and permit the oxygen forced back into said chamber, to pass away to the atmosphere while the passage of acetylene gas through the pipe g, g^1 , into the chamber b , is prevented by the water seal formed therein.

By this means the water in the two chambers will form a double safety valve whereby it is impossible for an explosion to occur through a mixture of oxygen and acetylene gas remaining in the apparatus.

What I claim as my invention and desire to obtain by Letters Patent is:—

1. A back pressure release valve comprising two separate chambers, an inlet pipe for gas leading into one chamber at its upper part and extending to a point near its base, said pipe having an opening within said chamber at its lower end, a transfer pipe leading from said chamber at a level disposed above the lower end of said inlet pipe, and leading into a second chamber wherein its end passes downwardly, to a point near the base of said chamber, an opening at the lower end of said pipe, a gas escape pipe having its lower end disposed within the second chamber at a point near its base, an opening in said lower end, said pipe passing upwardly through said chamber and having its upper end open and disposed exterior to said chamber, and an outlet passage leading from said second chamber at a level above the lower end of said escape passage.

2. A back pressure release valve comprising two separate chambers, an inlet passage for gas leading into one chamber and ex-

tending to a point near its base, said passage having an opening within said chamber at its lower end, a transfer passage leading from said chamber at a level disposed above the lower end of said inlet passage, and leading into the second chamber wherein its end passes downwardly to a point near the base of said chamber, an opening at the lower end of said passage, a gas escape passage having its lower end disposed within the second chamber at a point near its base, an opening in said lower end, said passage passing upwardly and having its upper end open and disposed exterior to said chamber, an outlet passage leading from said second chamber at a level above the lower end of said escape passage, and valve controlled openings in each of said chambers at a level disposed below the upper end of the transfer passage and above the lower end of the transfer passage.

3. A back pressure release valve comprising two separate chambers, an inlet passage for gas leading into one chamber and extending to a point near its base, said passage having an opening within said chamber at its lower end, a transfer passage leading from said chamber at a level disposed above the lower end of said inlet passage, and leading into the second chamber wherein its end passes downwardly to a point near the base of said chamber, an opening at the lower end of said passage, a gas escape passage having its lower end disposed within the second chamber at a point near its base, an opening in said lower end, said passage passing upwardly and having its upper end open and disposed exterior to said chamber, an outlet passage leading from said second chamber at a level above the lower end of said escape passage, and valve controlled openings in each of said chambers at a level disposed below the upper end of the transfer passage and above the lower end of the transfer passage, liquid in the base of each chamber below the upper end of said transfer passage.

ANGUS KENNEDY.
